PISTOL HOLSTER

John R. Couper, Denver, Colo., assignor to J. C. & G.
Ltd., a corporation of Colorado

Filed Oct. 23, 1965, Ser. No. 87,882

Term of patent 14 years

(Cl. D22—13)

Fig. 1

Fig. 2

Fig. 6

Fig. 3

Fig. 4

Fig. 5

Fig. 7

FIG. 1 is a front elevational view of my design for a pistol holster;

FIG. 2 is a left edge view of the holster;

FIG. 3 is a back elevational view of the holster;

FIG. 4 is a right edge view of the holster;

FIG. 5 is a plan view of the holster;

FIG. 6 is a front elevational view, similar to FIG. 1 but illustrating the holster as being in the open position; and

FIG. 7 is a bottom view of the holster.

I claim:

The ornamental design for a pistol holster, as shown.
